US00D968403S

(12) **United States Design Patent** (10) **Patent No.:** **US D968,403 S**
Jung et al. (45) **Date of Patent:** ** *Nov. 1, 2022

(54) **MONITOR FOR COMPUTER**(71) Applicant: **Samsung Electronics Co., Ltd.**, Suwon-si (KR)(72) Inventors: **Minjoon Jung**, Seoul (KR); **Taeyeon Won**, Seoul (KR)(73) Assignee: **SAMSUNG ELECTRONICS CO., LTD.**, Gyeonggi-Do (KR)

(*) Notice: This patent is subject to a terminal disclaimer.

(**) Term: **15 Years**(21) Appl. No.: **29/637,581**(22) Filed: **Feb. 20, 2018****Related U.S. Application Data**

(62) Division of application No. 29/594,919, filed on Feb. 23, 2017, now Pat. No. Des. 827,643.

CLAIM

The ornamental design for a monitor for computer, as shown and described.

DESCRIPTION

FIG. 1 is a front perspective view of a monitor for computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another front view thereof in an environment of use; and

FIG. 10 is an enlarged left-side view of the area indicated in FIG. 4; and,

FIG. 11 is an enlarged left-side view of the area indicated in FIG. 5.

The even-dash broken lines in FIGS. 3-5 and 8-11 depict portions of the monitor for computer and form no part of the claimed design. The even-dash lines in FIG. 9 show environment and form no part of the claimed design. The dash-dot lines in FIGS. 4-5 and 10-11 represent the boundaries of the detail views and form no part thereof.

FIG. 1

FIG. 2

FIG. 3

FIG. 5

FIG. 4

FIG. 6

FIG. 7

FIG. 8

FIG. 9

FIG. 11

FIG. 10
